UNITED STATES PATENT OFFICE.

JAMES T. COWLEY, OF LOWELL, MASSACHUSETTS, ASSIGNOR TO THE
LAMSON CONSOLIDATED STORE SERVICE COMPANY, OF NEWARK,
NEW JERSEY.

PNEUMATIC-DESPATCH-TUBE APPARATUS.

SPECIFICATION forming part of Letters Patent No. 657,092, dated September 4, 1900.

Application filed May 8, 1899. Renewed March 12, 1900. Serial No. 8,398. (No model.)

To all whom it may concern:

Be it known that I, JAMES T. COWLEY, of Lowell, in the county of Middlesex and State of Massachusetts, have invented certain new and useful Improvements in Pneumatic-Despatch-Tube Apparatus, of which the following is a specification.

My invention relates to improvements in pneumatic-despatch-tube apparatus in which the carriers are propelled through a single tube in both directions by air-pressure behind the carrier.

My invention consists of certain novel features hereinafter described, and particularly pointed out in the claims.

In the accompanying drawings, which illustrate a construction embodying my invention, Figure 1 is a sectional elevation of a discharging and receiving terminal located at one end of the line. Fig. 2 is a sectional view through the terminal on the line 2-2, Fig. 1. Fig. 3 is a plan view looking down on the top of the terminal. Fig. 4 is a sectional view of the air-passages hereinafter described. Fig. 5 is a side elevation showing the line and terminals at both ends of the line, which are similar in construction to that shown in Fig. 1. Fig. 6 is a detail sectional view of the plunger hereinafter described. Fig. 7 is a cross-sectional view through the plunger on the line X-X, Fig. 6.

Like letters of reference refer to like parts throughout the several views.

When it is desired to despatch a carrier, it is inserted into the terminal A at the inlet B, controlled by the valve C, pivoted to the lever C', which in turn is pivoted to the terminal A at C² and is held in its closed position by the spring C³, and the carrier passes down through the tube D and through the valve-box D' into the despatch-tube D², secured to the bottom plate D³ of the valve-box D'. The valve E is then closed to the position shown in dotted lines, Fig. 1, against the valve-seat E'. This valve E is pivoted to the lever E² at E³, and the upper part of this lever E² is secured fast to the shaft F, journaled in the side of the valve-casing. On this shaft F and projecting downwardly is a lever F', and bearing

against the lower end of this lever is another lever G', the upper end of which is mounted loosely on the shaft G², journaled in the sides of the terminal. On the shaft G² is securely fastened the lever H, provided at its outer end with the roll H', mounted on the journal-pin H². Between the levers G' and H is located the spring G³ to hold said levers normally in the position shown in Fig. 1 relative to one another. In order that the valve E may be closed, as above described, the handle J, secured fast to the shaft G², is moved forward toward the left from the position shown in dotted lines, Fig. 1, moving with it the shaft G², to which the lower end of the lever H is secured, and through the medium of the spring G³ and the lever G' the lever F' and the valve E are moved up to close the valve E, thereby closing the tube D, which communicates through the valve-box D' with the despatch-tube D².

Located in the pocket K and secured to the plate K' is a plate K², provided with the hub K³, within which is mounted the plunger K⁴, provided at its top with the flange K⁵, against which the roll H' of the lever H bears. Within the pocket K is mounted the piston-plunger L, held in a raised position by the spring L', as shown in Fig. 1. This plunger L is provided with a hollow stem L², to which the valve L³ is secured by the nuts L⁴, and the lower end of the valve-stem L² has an opening L⁵ communicating with the pocket M, which is in communication with the pressure-supply pipe M', secured to the bottom plate D³ of the valve-box D'. The spring L⁶ tends to keep the plunger K⁴ in the position shown in Fig. 1. The flange L⁷ on the stem L² limits the downward movement of the piston-plunger L in the pocket K. The plunger K⁴ is provided with a hollow passage K¹¹ and with a circular groove K⁷, which communicates with the vent K⁶ in the hub K³ when the parts are in the position shown in Fig. 1.

K⁸ is a cushion against which the flange L⁷ stops when the piston-plunger L reaches its lowest position. The upper curved portion A' of the terminal has an opening A² for the passage of the carriers into a suitable receptacle.

Said opening is closed by the valve A⁸, secured to the lever A⁴, to which is secured the valve A⁵, closing the opening A⁶. This valve A⁵ is secured to the lever A⁷, pivoted at A⁸ to the lugs A⁹ on the plate A¹⁰. This balance-valve is similar and operates in the same manner as that shown in United States Patent No. 527,073, dated October 9, 1894.

Extending across the outlet from the terminal in the line of the traveling carriers is a lever N, mounted on the pin N', secured to the sides of the terminals, and said lever is provided with an extension N², pivoted at N³ to the lever N⁴, which in turn is pivoted at N⁵ to the link N⁶, which is pivoted at N⁷ to the casing of the terminal A. The opposite end of said link is pivoted at N⁸ to the link N⁹, which at its lower end is pivoted at O' to the valve-plunger O, reciprocating in the cylinder O². On said cylinder is the plate O³ for supporting the rubber diaphragm O⁴, secured by the ring O⁵ to the plate O³. The plate O¹⁰ is secured to the shaft O⁶ and is held in contact with the rubber diaphragm by the spring O⁷, the shaft O⁶ working freely in the support O⁸, and is pivoted at O⁹ to the pivoted catch P. This catch P is in position to engage with the flange K⁵ when the plunger K⁴ is depressed, and by reason of air-pressure in the pipe Q³, passing through the connections Q² and Q' into the circular channel Q and acting against the diaphragm O⁴, the catch is held in engagement with the flange K⁵. This pipe Q³ is connected to the air-pressure supply-pipe M², (see Fig. 5,) which is connected to a suitable reservoir.

Assuming that a carrier has been inserted in the terminal A and is in the tube D², the valve E is closed by the movement of the lever J, lever H, and spring G³. The movement of said lever J and lever H will push down the plunger K⁴ until the ports K⁹ are in alinement with the spaces above the piston-plunger L in the box K, at which time the valve E is closed to prevent the air-pressure escaping through the terminal. The air passing from the chamber M up through the valve-stem L² will pass through the passage K¹¹ in the plunger K⁴ and out through the ports K⁹ above the piston-plunger L, and by reason of the area of this piston-plunger L being greater than the area of the valve L³, the valve L³ will be opened by the downward movement of the piston-plunger L and air will be admitted into the valve-box D' and the transmitting-tube D² and will force the carrier to the opposite end of the line. The said air-pressure in the valve-box D' will hold the valve E in its closed position (shown in dotted lines) after the lever J is released. The carrier traveling along the transmitting-tube D² will enter the terminal at the left hand of Fig. 5, which is identical in construction and operation to that shown in Fig. 1, and in its movement around the curved portion A' of the terminal will strike the lever N, and by reason of the connections N², N⁴, N⁶, and N⁹ the valve-plunger

O will be raised. The lower end of this plunger passes above the circular chamber Q, allowing the pressure in the circular chamber 7^c to escape through the bottom of the cylinder O². The air-pressure in the pipe Q³, communicating with the circular chamber Q, is admitted through the valve S, Fig. 5, which is only slightly open to admit a very small 7^d quantity of air, so that when the plunger O is raised, allowing the pressure to escape as above described, the outlet for the air in the pipe Q³ will be so much greater than the inlet at the valve S that the pressure in the pipe 8^c Q³ will immediately drop the whole length of the pipe. Consequently the pressure will be removed at the despatch end of the line from the diaphragm O⁴, allowing the spring O⁷ to exert its force to pull the catch P away from the flange K⁵ on the plunger K⁴, releasing the plunger K⁴, which will immediately be raised by the action of the spring L⁶. This raising of the plunger K⁴ will shut off the ports K⁹ from communication above the piston-plunger L, thus allowing the spring L' to raise the plunger to the position shown in Fig. 1 and closing the valve L³, cutting off the air-pressure from the valve-box D' and transmitting-tube D². As soon as this air-pressure is cut 9^c off the valve E will immediately drop by gravity to the position shown in full lines, Fig. 1, to allow the insertion of the carriers into the transmitting-tube D². This release of the plunger K⁴ will move the ports K⁹ out 10^c of alinement with the upper part of the pocket K and will also bring the circular groove K⁷ into alinement with the vent K⁶ in the hub K³ on the plate K². The vertical slot K¹⁰ in the periphery of the plunger K⁴ communicates with the groove K⁷ and will in this position form a vent for the upper part of the pocket K, allowing the air to escape out through the vent K⁶. It will be seen with the parts in the position shown in Fig. 1 that the air-pressure from the pocket M is cut off from the upper part of the pocket K and that also a vent is formed for the upper part of the pocket K to allow the escape of the air from said upper part through the vent K⁶, 11^c when the spring L' will force the plunger L, carrying with it the valve L³, upwardly to the position shown in Fig. 1, thereby closing the opening from the pocket M and preventing the further flow of air into the despatch-tube D².

Assuming that a carrier is to be despatched at the left hand of the line shown in Fig. 5 in a manner identical to that described when sending from the right-hand end illustrated in 12^c section in Fig. 1, the carrier will pass up through the tube D² into the tube D, around the curved portion A', strike the lever N, and through the connections N², N⁴, N⁶, and N⁹ the valve-plunger O will be raised and the 13^c air-pressure shut off from the discharge end of the line as above described, the carrier by its momentum opening the valve A³ and passing out into a suitable receptacle, and the

valves A³ and A⁵ will immediately close the openings A² and A⁶ and prevent the air escaping. As the carrier is traveling toward the right-hand terminal the air ahead of the carrier is forced along by said carrier and passes through the terminal, through the passages R, R', and R², and escapes into the atmosphere by the outlet R³. This arrangement provides for carrying off the air ahead of the carrier and avoids the objectionable feature of the air blowing onto the desk in front of the operator. The valves T are located in the air-pressure supply-pipe M' in order that the volume of air may be regulated.

15 I do not limit myself to the arrangement and construction shown, as the same may be varied without departing from the spirit of my invention.

Having thus ascertained the nature of my invention and set forth a construction embodying the same, what I claim as new, and desire to secure by Letters Patent of the United States, is—

1. In a pneumatic-despatch-tube apparatus, a carrier-transmitting tube having an inlet and an outlet for the carriers, a valve for closing said inlet after the insertion of the carriers, a source of compressed air, an air-inlet for said compressed air, a valve normally closing said air-inlet, means for opening said air-inlet valve adapted to be operated to open said valve upon the closing of the valve controlling said carrier-inlet, means operated by compressed air for holding said air-inlet valve open, and mechanism in the path of the traveling carriers adapted to be operated by the carriers to release the air-pressure on said air-inlet-valve-holding means and thereby release the same to allow the closing of said air-inlet valve.

2. In a pneumatic-despatch-tube apparatus a carrier-transmitting tube having an inlet and an outlet for the carriers, a valve for closing said inlet after the insertion of the carriers, a source of compressed air, an air-inlet for said compressed air, a valve normally closing said air-inlet, means for opening said air-inlet valve adapted to be operated to open said valve upon the closing of the valve controlling said carrier-inlet, means operated by compressed air for holding said air-inlet valve open, mechanism in the path of the traveling carriers adapted to be operated by the carriers to release the air-pressure on said air-inlet-valve-holding means and thereby release the same to allow the closing of said air-inlet, and yielding means acting on said air-inlet-valve-holding means for preventing the same from holding said air-inlet valve open upon the release of said air-pressure.

3. In a pneumatic-despatch-tube apparatus, a carrier-transmitting tube having an inlet and an outlet for the carriers, a valve for closing said outlet after the insertion of the carriers, a lever for closing said valve, a shaft on which said lever is loosely mounted, a han-

dle fast on said shaft adapted to be moved to operate said lever to close said valve, a yielding connection between said shaft and said operating-lever, a source of compressed air, 70 an air-inlet for the compressed air, a valve normally closing said air-inlet, mechanism for opening said air-inlet valve adapted to be actuated to open said valve upon the closing of the valve controlling said carrier-inlet, means 75 operated by compressed air for holding said air-inlet valve open, and mechanism in the path of the traveling carriers adapted to be operated by the carriers to release the air-pressure on said holding means and thereby 80 release said air-inlet valve to allow the closing of said air-inlet.

4. In a pneumatic-despatch-tube apparatus, a carrier-transmitting tube having an inlet and an outlet for the carriers, a valve for 85 closing said inlet after the insertion of the carriers, a source of compressed air, an air-inlet for the compressed air, a valve normally closing said air-inlet and provided with a hollow stem open to said compressed air and with 90 a piston-plunger of greater area than said valve, mechanism for opening said air-inlet valve, means operated by compressed air for holding said air-inlet valve open, means for establishing communication between said 95 source of compressed air and one side of the piston-plunger to open said air-inlet valve by the air-pressure acting on said piston-plunger, mechanism adapted to be operated by the traveling carriers for breaking said communication by releasing the air-pressure on said 100 air-inlet-valve-holding means and thereby release the same to allow the closing of said air-inlet, and means for returning said piston-plunger to its normal position. 105

5. In a pneumatic-despatch-tube apparatus, a carrier-transmitting tube having an inlet and an outlet for the carriers, a valve for closing said inlet after the insertion of the carriers, a source of compressed air, an air- 110 inlet for said compressed air, a valve normally closing said air-inlet and provided with a hollow stem open to said compressed air and with a piston-plunger of greater area than the valve, mechanism for opening said air-inlet 115 valve, means operated by compressed air for holding said air-inlet valve open, a plunger movable in said hollow stem and having passages for leading the compressed air to one side of the piston-plunger of greater area than 120 the valve to open said valve by the pressure acting on said plunger of greater area, mechanism for closing said carrier-inlet valve and for moving said plunger in said stem to establish the said communication for the compressed air, means operated by compressed air for holding said plunger in said hollow stem to maintain said communication for the compressed air to hold said air-inlet valve open, and mechanism in the path of the traveling carriers adapted to be operated by the carriers to release the air-pressure on said 130

air-inlet-valve-holding means and thereby release the same to allow the closing of said air-inlet valve.

6. In a pneumatic-despatch-tube apparatus, a carrier-transmitting tube having an inlet and an outlet for the carriers, a valve for closing said inlet after the insertion of the carriers, a source of compressed air, an air-inlet for said compressed air, a valve normally closing said air-inlet, means for opening said air-inlet valve adapted to be operated to open said valve upon the closing of the valve controlling said carrier-inlet, means operated by compressed air for holding said air-inlet valve open, a valve for controlling the escape of the compressed air acting on said air-inlet-valve-holding means, and mechanism in the path of the traveling carriers adapted to be operated by the carriers to move said valve to release the air-pressure on said air-inlet-valve-holding means and thereby release the same to allow the closing of the said air-inlet valve.
7. In a pneumatic-despatch-tube apparatus, a carrier-transmitting tube having an inlet and an outlet for the carriers, a valve for closing said inlet after the insertion of the carriers, a source of compressed air, an air-inlet for said compressed air, a valve normally closing said air-inlet, means for opening said air-inlet valve adapted to be operated to open said valve upon the closing of the valve con-

trolling said carrier-inlet, means operated by compressed air for holding said air-inlet valve open, and mechanism for releasing the air-pressure on said air-inlet-valve-holding means to release the same to allow the closing of the air-inlet valve.

8. In a pneumatic-despatch-tube apparatus, a carrier-transmitting tube having an inlet and an outlet for the carriers, a valve for closing said inlet after the insertion of the carriers, a source of compressed air, an air-inlet for said compressed air, a valve normally closing said air-inlet, means operated by compressed air for opening said air-inlet valve upon the closing of the valve controlling said carrier-inlet, means controlling the flow of compressed air to said valve-opening means, means operated by compressed air for holding said air-inlet valve open, and mechanism for releasing the air-pressure on said air-inlet-valve-holding means to release the same to allow the closing of the said air-inlet valve.

In testimony whereof I have signed my name to this specification, in the presence of two subscribing witnesses, this 6th day of May, A. D. 1899.

JAMES T. COWLEY.
